UNITED STATES PATENT OFFICE.

PAUL LOUIS HOCHON AND NICOLAS GJORGJEVITCH, OF PARIS, FRANCE; SAID GJORGJEVITCH ASSIGNOR TO SAID HOCHON.

TRANSPORTABLE POWER-WINCH.

1,243,292.

Specification of Letters Patent. Patented Oct. 16, 1917.

Application filed February 9, 1916. Serial No. 77,323.

To all whom it may concern:

Be it known that we, PAUL LOUIS HOCHON, a citizen of the French Republic, and NICOLAS GJORGJEVITCH, a subject of the King of Serbia, both residents of Paris, Seine, France, have invented certain new and useful Transportable Power-Winches, of which the following is a specification.

This invention relates to a portable power 10 winch and has for its object to construct such a winch in a compact form together with the motor for driving the same, such as an internal combustion motor or an electric motor, and the winding drum with suitable reduction gear, these all being mounted 15 on a base so that the whole structure may be easily transported where required.

A further object of the invention is to provide means for attaching the structure to the 20 ground in such a way that the point of attachment will always be in a straight line with the direction of the pull on the winding cable, in order that the winch will always work under the most favorable conditions.

Another object of the invention is the provision of a device for preventing the slipping back of the free end of the cable where it is unwound behind the drum if this end is 30 released by the man holding it.

The invention also has for its object to provide a device by means of which it is possible to arrest the movement of the load during its course, and to transfer the pull of the 35 load on the cable from the winding drum to the base, and thus to the point of attachment independently of the winch drum.

An additional object of the invention is the provision of a hand device by means of 40 which the winding drum can be turned in a reverse direction to that in which it is driven by the motor so that the coils around the drum can be loosened for example when it is desired to re-start the motor.

45 The apparatus is hereinafter described with reference to the accompanying drawings, in which:—

Figure 1 is a sectional elevation taken on the line A—B of Fig. 3;

50 Fig. 2 is an end view looking in the direction of the worm wheel;

Fig. 3 is a plan view;

Fig. 4 is a perspective view of the apparatus inclosed in its casing;

55 Fig. 5 is a partial end view to a larger

scale showing the device for turning the drum in a reverse direction;

Figs. 6 and 7 show to a larger scale a front view and side view of the attachment device connected by a short length of cable to the 60 structure and permitting the load to be relieved from the winch drum and transferred to the base of the apparatus and to the post fixed in the ground;

Fig. 8 is a detail view;

Fig. 9 shows to an enlarged scale a side view of the device for gripping automatically the free end of the cable if it is released by the man holding it;

Fig. 10 shows by way of example the use 70 of the apparatus for hauling a gun over sloping ground.

The apparatus comprises a base 1 furnished with hooks or rings 2 to facilitate its transport and manipulation when placing 75 it in position.

Upon the base 1 are secured two plates 3—3 between and in which are mounted and supported the principal elements of the mechanism. Between these plates 3—3 there is mounted between two smaller plates 5—5 a large worm wheel 4 of which the shaft 6 turns in two sleeves or bushes forming elongated bearings between the plates 3 and 5. Upon one end of the shaft 6 which 85 projects beyond one of the plates 3 is mounted the drum 7 of the winch.

The worm wheel 4 gears with a worm 8 cut upon the shaft 9 at right angles to the shaft 6 of the wheel 4. This shaft 9 is driven 90 from a motor, such as an internal combustion motor 10 of any suitable type, by means of a train of reduction gear 11. In the construction shown this reduction gear consists of a toothed wheel mounted upon the shaft 95 of the motor 10, a toothed wheel on the shaft 9 of the worm, and two toothed wheels upon a secondary shaft, parallel to the others. The invention, however, is not limited to this construction as it will be apparent that any suitable means may be employed to secure the necessary reduction between the motor and the worm shaft.

The worm 8 can also be rotated by hand in order to turn the wheel 4 with the drum 7 105 through a short distance in certain cases, for instance to turn it backwardly so as to loosen the windings of the cable around the drum. Such an operation may be useful, for example, in the case of the stoppage of 110

the motor when it is desired to re-start it; in such a case the pull of the load on the cable would first be relieved by means of the device hereinafter described. The hand device comprises a pinion 12 mounted upon the end of the shaft 9; with this pinion may gear a worm 13 upon a transverse shaft 14 turned by a crank 15; Fig. 5. This mechanism composed of the worm 13, shaft 14 and crank 15 need only be placed in position when it is desired to turn the drum in a reverse direction.

The apparatus is anchored to a post fixed in the ground by means of a cable 16, of which the ends are attached to one end of the base 1 by means of eyes 16¹ approximately equidistant from the line of the cable 24 where it runs on to the drum 7. The attachment cable 16 passes around a pulley 17 mounted on plates 18 which extend from a ring 19 adapted to be passed over a post driven into the ground; upon this post the whole pull of the apparatus and the load is taken. This arrangement is an important and characteristic feature of the invention. It insures that the pull is always exerted in a straight line from the object to be hauled to the point of attachment to the ground, under which the best conditions of working are obtained, and as the whole apparatus forms a block simply resting upon the ground it will swing relatively to the post and automatically set itself in such a manner that the line of the pull is always kept in a straight line from the object to be hauled to the post when the direction of the pull is changed, as this pull is generally greater than the resistance to movement over the ground due to the weight of the winch.

At the front end of the support 1 is provided a device for use when the pulling up of the load is stopped, and serving to relieve the pull thereof upon the drum of the winch, the pull being transferred to the base of the apparatus and from the latter to the post. This device is shown in detail in Figs. 6, 7 and 8, Fig. 8 being a partial plan view corresponding to Fig. 6, and showing the method of attachment of the short cable 20 adapted to transfer the pull directly to the base of the apparatus.

The device comprises a short length of cable 20 attached to the base 1 by an eye 20¹ disposed on the bisecting line of the angle between the two ends of the cable 16 attached to the post in the ground, that is to say, along the axis of the pull. At the other end of the cable 20 is fastened a member 21 having a jaw 22 adapted to receive the cable 24; this jaw has a recess at the center in which the cable can be gripped by means of the enlarged end of a screw 23 (Fig. 6). The member 25 is a locking member adapted to secure the loop in the cable 20 for attaching purposes.

Fig. 10 which shows an example of the use of the winch, indicates the mode of operation of the apparatus hereinbefore described. If for any reason it is desired to stop the haulage of the gun during its upward movement, it may be indispensable or advantageous immediately to relieve the pull which it exerts on the winch drum. For this purpose the screw 23 in the jaw 22 of the member 21 is caused to engage the cable 24 at the front of the winch, the cable being then slackened on the drum. Under these conditions the pull of the load is no longer exerted upon the part of the cable 24 behind the point of attachment of the cable 20, but the pull is transferred by the latter directly to the base of the winch and to the post.

Fig. 9 shows a device adapted automatically to check and hold the free end of the cable if the man releases it. This device consists of a block 27 mounted upon a fixed pivot 26 and carrying a movable jaw 28 pivoted at 30 upon the block 27, this jaw being acted upon at its end 29 by a spring 31. By means of this device the cable is left free to travel in the direction α as its free end is pulled in that direction, but if it is released and the cable is pulled in the direction γ by the load it will be gripped between the movable jaw 28 and the block 27. The whole device can slide laterally on the pivot 26, so as always to be in line with the free end of the cable no matter what number of turns of cable are on the drum.

The motor 10 is provided with all the usual accessories necessary for its operation; it is provided with a starting device and handle or a pulley 10¹ adapted to receive a starting belt. The motor may be cooled by water or air. This latter method which permits of a considerable reduction in weight is the most convenient in a number of cases, the more so if the motor is not required for continuous working. The motor is provided with a fan 10² suitably placed. The fuel and oil reservoirs are provided at 32—33 between the plates 3. The whole structure is inclosed in a casing suitably perforated for the circulation of air and with holes 32¹, 33¹ for giving access to the reservoirs for filling purposes and so forth.

The apparatus thus constructed forms a compact structure which can be handled and transported easily. Such an apparatus can be used for various purposes, in workshops, docks and so forth, and it is especially useful for military purposes as already indicated.

The invention is not limited to the details of construction described, and as will be well understood it may be carried into effect with various modifications in details without departing from the spirit of the invention.

Having thus described our invention what

we claim as new and desire to secure by Letters Patent is:—

1. The combination with a transportable power winch comprising a base, a motor mounted on said base, a winding drum mounted on said base and driven by the motor, and reduction gear between the motor and the winding drum, of gear for turning the winding drum in a reverse direction to 10 that in which it is driven by the motor, means for transferring the pull of the load from the winding drum to the base, and means for attaching the base to the ground, said means being such that the winch can 15 swing laterally so as to keep the winding drum in a straight line between the point of attachment and the direction of the pull of the load.

2. A transportable power winch comprising a base, a motor mounted on said base, plates fixed to said base, a shaft mounted

in said plates and at one side projecting beyond said plates, a worm wheel mounted on the shaft between the plates, a winding drum mounted on the projecting end of the shaft, a worm shaft, a worm thereon gearing with the worm wheel, reduction gear between the motor and the worm shaft, a cable adapted to be wound on the drum, means for gripping the free end of the cable 25 beyond the drum when released, means for transferring the pull of the load on the cable from the drum to the base, and means for securing the base to a post fixed in the ground, said means being such that the winding drum will always be in a straight line 30 with the direction of the pull on the cable. 35
